United States Patent

Des. 241,839
Patented Oct. 12, 1976

241,839

DOWNRIGGER

James A. Kammeraad, Holland, Mich., assignor to
DFK Inc., Holland, Mich.

Filed May 22, 1975, Ser. No. 579,890

Term of patent 14 years

Int. Cl. D22—05

U.S. Cl. D22—26

FIG. 1 is a perspective view of a downrigger showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is an elevational view of one side thereof; and

FIG. 7 is an elevational view of the other side thereof.

I claim:

The ornamental design for a downrigger, as shown.
